(74) Attorney, Agent, or Firm — CANTOR COLBURN
LLP(57) **CLAIM**

The ornamental design for fracture prevention garment as shown and described.

DESCRIPTION

1. Fracture prevention garment

1.1 : Top

1.2 : Right

1.3 : Perspective

1.4 : Bottom

1.5 : Back

1.6 : Perspective

1.7 : Left

1.8 : Front

The feature bounded by the broken line in 1.1 forms no part of the claimed subject matter.

1 Claim, 8 Drawing Sheets
